UNITED STATES PATENT OFFICE.

OTTO A. DEICHMANN, OF WILLOWS, CALIFORNIA.

BUILDING CONSTRUCTION.

1,400,144.

Specification of Letters Patent. Patented Dec. 13, 1921.

Application filed January 26, 1921. Serial No. 439,806.

To all whom it may concern:

Be it known that I, OTTO A. DEICHMANN, a citizen of Germany, residing at Willows, in the county of Glenn and State of California, have invented new and useful Improvements in Building Constructions, of which the following is a specification.

This invention relates to building construction, and more particularly pertains to 10 a pre-cast element by which walls may be readily formed.

It is the principal object of the present invention to provide pre-cast elements made of cementitious or vitreous material, and so 15 formed as to make it possible for the elements to be readily arranged in courses and in interlocking relation to each other in a manner to produce outer walls, partitions, and the like, at the same time accommodat- 20 ing door frames, window frames, and other building structures.

The present invention contemplates the use of T-shaped elements adapted to be arranged in courses, and in interlocking relation to each other, whereby a hollow wall will be formed, broken at intervals by brace members and sealed at the top and bottom by base and cover blocks, modifications of the 25 principal element being made to form wall 30 intersections and wall openings.

The invention is illustrated by way of example in the accompanying drawings, in which:

Figure 1 is a view in perspective disclosing the principal element of the present invention.

Fig. 2 is a view in perspective showing one of the cover blocks.

Fig. 3 is a view in perspective showing 40 one of the base blocks.

Fig. 4 is a view in perspective disclosing a modification of the member illustrated in Fig. 1, for the purpose of forming wall openings and the like.

Fig. 5 is a view in plan section showing the application of the member disclosed in Fig. 4.

Fig. 6 is a view in plan showing the interlocking arrangement of the principal elements.

Fig. 7 is a fragmentary view in side elevation showing the courses of the principal elements as they appear in a wall.

Fig. 8 is a view in vertical section dis- 55 closing an adaptation of the present invention in building construction.

Fig. 9 is a view in section and elevation showing the plan of reinforcing pilasters.

Fig. 10 is a fragmentary view in plan showing a wall intersection.

Fig. 11 is a view in plan section showing the manner in which a doorway is formed.

Referring more particularly to the drawings, 10 indicates the principal element of the present invention, hereafter designated 65

as the wall element. This member is formed by a slab 11 from the side of which emanates a connecting and reinforcing wing 12. This 70

wing is disposed midway the length of the element. The outer end of the wing is 75

formed with an enlarged head 13, which considered in plan is substantially hexagonal. The slab 11 is used with its length extending horizontally as it rests upon its edge. The 80

lower edge of the slab is formed with a V-shaped recess 14 extending the length thereof, while the upper edge of the slab is formed with a V-shaped rib 15 adapted to 85

be received by a recess 14 of a slab, which might be subsequently disposed thereon, the 90

opposite ends of the slab of each being formed with V-shaped recesses 16, extending the height of the slab. The hexagonal 95

head of the wing 13 is formed at its bottom with a V-shaped recess 17 parallel to the recess 14, while its top is formed with a V-shaped rib 18 parallel to the rib 15 of 100

the slab. Due to the hexagonal formation of the head 13, the sides of the head will consist of two planes disposed at an angle 105

to each other, agreeing substantially with the faces of the end recesses 16 in the slabs. In this manner it is possible to alternately 110

arrange the slabs as indicated in Fig. 6, so that the space between intervening recesses 16 of two slabs may form a properly shaped pocket for the accommodation of the heads 13 of wings 12. When cementitious material is then disposed between the side faces 100

of the heads and the faces of the recesses 16, the several elements of a course will be locked and cemented together. In addition to this, intervening air spaces 19 will be 105

formed between the slabs 11 and will be interrupted by the cross wings 12. These air spaces may be further broken by offsetting the various courses of tile so that the cross 110

wings of the slabs do not occur in vertical alignment. Due to the recesses and ribs 14, 15, 17 and 18, it will be understood that the wall elements of the various courses will be suitably interlocked and will be held against

lateral movement, in order that the air spaces 16 may be properly crossed and that the top and bottoms of the wall may be satisfactorily finished. Base blocks 20 are provided, as well as cover blocks 21. The base blocks are formed with a plurality of ribs 22, agreeing with the recesses 14 and 17 in the wall elements. This makes it possible to suitably support and anchor the wall. The 10 cover blocks 21 are formed with recesses 23 for receiving the uppermost ribs 15 and 18 of the wall elements. Ribs 24 are also formed on these blocks, so that they may be used at other places in the building if desired. In some instances it may be desirable to form modifications of the blocks 21 as indicated by way of example at 25 and 26 in Fig. 8. The opposite ends of the various blocks are of course formed with complementary ribs and recesses by which they may be interlocked when arranged in courses.

In forming door and window openings it is necessary to modify the construction of the wall elements as shown in Fig. 4 and 25 Fig. 11. The window element 27 shown in Fig. 4 is made with a short slab, at the end and side of which the wing 12 is formed. This provides a flush face against which the window frame is set. The element 23 30 is quite similar to this structure and differs only in the use of an extending wing 29 formed as a continuation of the slab, the object of which structure is more clearly shown in Fig. 11.

35 In making proper intersections of walls formed by the elements previously described, an intersecting element 30 is provided. This element in reality comprises four slabs arranged at right angles to each other and emanating from a central square block, the slabs being continuations of the walls thereof. The tops and bottoms of the element are grooved and ribbed in the manner previously described for the other elements, 40 while the ends of each of the slabs are vertically grooved to accommodate the heads of adjacent wall elements. Vertical ribs 31 are formed upon the opposite sides of the block and are adapted to mesh with vertical grooves 16 on the ends of the wall elements.

In the event that a very rigid reinforced wall is desired, the structure might be built up as shown in Fig. 9, where it will be 55 seen that ferro-concrete construction is employed between the wall elements. Columns 32 may also be formed by the use of an offset member 33, which interlocks with the heads of two of the wall elements and provides a large rectangular opening, within 60 which concrete and reinforcing material may be poured to form supporting columns of any desired strength.

In operation of the present invention, it 65 will be understood that prior to the erection

of the building, appropriate wall slabs and other special slabs are ordered as required. After a suitable foundation has been made, the base blocks 20 may be mounted thereupon, and the wall members thereafter 70 superposed upon the base block, as particularly disclosed in Fig. 8. Intersections of walls may be made up as indicated in Fig. 10, while window and door openings are constructed and framed as more clearly 75 shown in Figs. 5 and 11. Due to the fact that the slabs of the wall elements will be held in spaced relation to each other, a double wall will be formed having air spaces in the center thereof, which spaces 80 may be subdivided by the transversely extending wing elements 12.

It will thus be seen that by forming elements of plastic or cementitious material in the design disclosed in the drawings, it 85 will be possible to readily assemble the elements to provide suitable walls for various classes of buildings, said walls being of such construction that stucco work may be applied to the outside thereof and plastering 90 on the inner faces thereof, without the use of furring strips and the like, thereby providing means for economically and rapidly building durable fire proof walls.

While I have shown the preferred form 95 of my invention, as now known to me, it will be understood that various changes might be made in the combination, construction, and arrangement of parts, by those skilled in the art, without departing from the spirit 100 of the invention, as claimed.

Having thus described my invention, what I claim and desire to secure by Letters Patent is:

1. In a wall structure a building element 105 comprising a slab of plastic material having a V-shaped rib extending along its upper edge, a V-shaped groove extending along its lower edge and V-shaped grooves extending vertically along the ends thereof, a wing 110 member of rectangular section emanating from one side of the slab and midway the length thereof, and an enlarged head substantially hexagonal in section formed upon the end of the wing. 115

2. In a wall structure a building element comprising a slab of plastic material having a V-shaped rib extending along its upper edge, a V-shaped groove extending along its lower edge and V-shaped grooves extending 120 vertically along the ends thereof, a wing member of rectangular section emanating from one side of the slab and midway the length thereof, and an enlarged head formed at the end of said wing, having a V-shaped 125 rib across the top thereof and a V-shaped groove across the bottom thereof, and V-shaped ribs extending vertically on the opposite sides thereof to seat within vertical grooves of complementary slabs. 130

3. A fire-proof wall structure comprising base blocks of plastic material adapted to interlock at their opposite ends, and being formed with parallel longitudinal V-shaped 5 ribs on the upper faces thereof, T-shaped wall elements adapted to be superposed in courses upon said base blocks, said elements having grooved lower edges seating over the ribs of the base blocks and successively seating 10 over similar ribs formed along the upper edges of the wall elements in the various courses of the wall, the slabs of said elements being built up in spaced relation to each other upon the parallel ribs of the base blocks, 15 interlocking wings extending from the inner faces of alternate slabs and terminating between the ends of slabs in the opposite rows and cover blocks having parallel recesses in their lower faces to register with the parallel 20 ribs on the wall elements of the uppermost course of the wall.
4. A fire-proof wall structure comprising base blocks of plastic material adapted to interlock at their opposite ends, and being 25 formed with parallel longitudinal V-shaped ridges on the upper face thereof, T-shaped wall elements adapted to be superposed in courses upon said base blocks, said elements having grooved lower edges seating over similar ribs formed along the upper edges 30 of the wall elements in the various courses of the wall, the slabs of said elements being built up in spaced relation to each other upon the parallel ribs of the base blocks, a wing member of rectangular section emanating from the inner side of alternate slabs and the outer side of the intermediate slabs midway the length thereof, and an enlarged head formed at the end of said wing having a V-shaped groove across the bottom thereof, 35 a V-shaped ridge formed along the top and sides of said enlarged head, the said head being positive between the ends of the slabs in the opposite row which are formed with recesses adapted to register with the ridges 40 along the side of the enlarged head, and cover blocks having parallel recesses in their lower faces to register with the parallel ridges on the assembled wall elements of the uppermost course of the wall.

OTTO A. DEICHMANN.
